UNITED STATES PATENT OFFICE

IDA BING, OF NEW YORK, N. Y.

BRUSH.

1,016,734.

Specification of Letters Patent.

Patented Feb. 6, 1912.

Application filed April 2, 1910. Serial No. 553,020.

To all whom it may concern:

Be it known that I, IDA BING, a citizen of the United States, residing at New York, borough of the Bronx, in the county of New

5 York and State of New York, have invented certain new and useful Improvements in Brushes, of which the following is a specification, reference being had therein to the accompanying drawing.

10 My invention relates to improvements in brushes and has for its object to provide a simple, effective and economic means for securing the bristles or wires of the same.

15 In the accompanying drawings, Figure 1 is a vertical cross section of a brush with part of the handle broken away. Fig. 2 a section of the same at right angles. Fig. 3 a cross section on the line 3—3 of Fig. 1. Fig. 4 a plan view of a cleat used for securing the bristles or wires, and Fig. 5 a view 20 looking from right to left at the same.

6 is the handle of the brush having a groove 7 cut in the end of the same.

25 8 is another groove cut at right angles thereto large enough to receive the cleat 9 shown in Fig. 4. This cleat is preferably provided with a rectangular opening 10 through which the wires or bristles may be introduced and 11 is a hole to receive the 30 pin 12 after the cleat is in position.

In constructing the brush, the cleat 9 is driven into position and secured by the pin 12 after which the wires or bristles 13 are

passed through the same and fitted snugly into the grooves formed by the cut 7 after 35 which they may be bound in position by a binder such as the wire 14.

Of course it will be understood that various modifications may be made without departing from the spirit of the invention as 40 set forth in the claims.

Having described my invention, what I claim as new, and desire to secure by Letters Patent is:

1. In a tool of the class described, a handle 45 having transverse cuts in the end thereof, a holding member having an opening and adapted to engage one of said cuts and means for securing the same therein and wires or bristles through said opening in 50 said holding member and adapted to set within the end of said handle, and means for binding the combination in position.

2. In a tool of the class described, a handle 55 provided with cuts in the end thereof, a cleat adapted to engage one of said cuts, wires or bristles adapted to penetrate said cleat and engage the other of said cuts and a binder to retain said wires or bristles in said other of said cuts.

In testimony whereof I affix my signature in presence of two witnesses.

IDA BING. [L. S.]

Witnesses:

LIZZIE WEISS,
SIGMUND ROLLMIK.
